REMOVABLE WEDGE BOLT

Filed Nov. 11, 1927

UNITED STATES PATENT OFFICE.

FRANK C. McENERNY, OF COLUMBUS, OHIO, ASSIGNOR OF ONE-THIRD TO LOUIS BERN-HARD AND ONE-THIRD TO H. E. RICHTER, BOTH OF COLUMBUS, OHIO.

REMOVABLE WEDGE BOLT.

Application filed November 11, 1927. Serial No. 232,700.

This invention relates to improvements in removable wedge bolts for locomotive frame pedestals, and has for its primary object the provision of a wedge bolt construction which 5 may be removed from its operative position in connection with the pedestal frame and pedestal brace without first requiring the removal of the brace to effect the operation.

As locomotives are now ordinarily constructed it is a matter of very considerable time and labor to remove defective wedge bolts for the purpose of adjusting the axle boxes or blocks and therefore the present invention consists in the provision of a simple 10 and improved type of wedge block wherein the operating bolts thereof when worn or damaged may in a few minutes' operation be removed and replaced without disturbing the general assembly of associated parts and in 15 but a small fraction of the time are required for effecting similar replacements.

With these and other objects in view, as will appear as the description proceeds, the invention consists in the novel features of 20 construction, combinations of elements and arrangements of parts hereinafter to be more fully described and pointed out in the appended claims.

In the accompanying drawing:

30 Figure 1 is a vertical sectional view of a portion of a locomotive frame, illustrating the construction and position of the improved wedge bolt comprising the present invention in association therewith,

35 Figure 2 is a vertical transverse sectional view taken on the plane indicated by the line 2-2 of Figure 1,

Figure 3 is a horizontal sectional view on the line 3-3 of Figure 1,

40 Figure 4 is a similar view taken on the plane indicated by the line 4-4 of Figure 2,

Figure 5 is a horizontal sectional view on the line 5-5 of Figure 2,

45 Figure 6 is a detail perspective view of the head end of the removable bolt.

Referring more particularly to the drawing the numeral 1 designates a portion of the frame of a locomotive, the frame being formed to include the usual pedestal bars 2, 50 a removable pedestal brace 3, axle blocks 4 and an axle 5. The removable pedestal brace 3 is provided with the usual sockets 6 for the reception of lugs 7 which depend from the frame 1, and bolts 8 are utilized in the usual

way for securing the brace 3 to the bars of 55 the pedestal frame.

Interposed between the pedestal legs 2 is a wedge 9 of substantially standard construction, which by being adjustable vertically with respect to the frame is adapted to tighten 60 the position of the axle blocks 4 in the customary manner. In this instance, however, the bottom of the wedge 9 is formed to include a transversely extending substantially T shaped slot 10 having notches 11 provided 65 therein intermediate of its length. The slot 10 extends from one side of the wedge bar to the other, as indicated in Figures 1 and 4.

Receivable within the slot 10 is the head 12 of a securing bolt 13. This head possesses 70 important dimensions in that the length thereof exceeds the width of the restricted portion 14 of the slot 10, so that when the bolt 13 is actively positioned the head thereof will be received within the notches 11 and will extend 75 transversely of the slot 10 as shown in Figure 5. By thus proportioning the head 12 it will be seen that the same may be rotated within the slot 10 so as to be aligned with the restricted portion 14 thereof, which 80 will permit the bolt to be withdrawn from engagement with the wedge and likewise to be conveniently inserted in connection therewith.

The bolt is provided with an elongated shank which is receivable within an exteriorly threaded sleeve or bushing 15, the latter, in turn, being threaded into an opening 16 extending vertically through the removable pedestal brace 3. A lock nut 17 is provided on the exterior of the bushing or 90 sleeve 15 to retain the latter against loss of adjustment. The bottom of the bolt 13 or the lower end thereof is threaded as at 18 for the reception of one or more binding nuts 19, which engage with an annular enlargement 95 20 formed upon the lower end of the bushing or sleeve 15, so that by tightening the nuts 19 the wedge block 9 may be advanced into firm frictional engagement with the axle journals and pedestal frames.

The diameter of the opening 16 is in excess of the greatest diameter of the head 12, and it will be seen that when the bushing or sleeve 15 has been removed from the pedestal brace 3, it is a simple matter to slightly elevate the 105 head 12 of the bolt 13 so as to remove the same from the notches 11. Then by rotating the bolt 13 to approximately 90 degrees or

one-quarter turn, the longest part of the head 12 will be aligned with the restricted portion 14 of the slot 10. This enables the head 12 to then pass through the restricted portion 5 of said slot and since the head is smaller in diameter than the opening 16, it follows that the entire bolt may be withdrawn through the pedestal brace and entirely removed from the assembly, this being accomplished without in 10 any way disturbing the operating position of the wedge 9, the axle block 4, or the pedestal brace 3. All of these parts are retained in their normal assembled positions of operation and it is only necessary to remove the bushing or sleeve 15 and the bolt 13 to provide for substitution of parts. It should be observed that these wedge bolts are constantly becoming worn, bent, twisted and mutilated during the operation of the locomotive and 15 when so damaged the same can not be used to adjust the wedges and axle boxes. It is therefore necessary to continually replace the same. In standard constructions heretofore in use this has involved the removal of 20 the pedestal brace and the placing of the locomotive out of service for several hours' time. By the use of the present invention, however, the replacement of such bolts is reduced to a simple, quickly and easily accomplished 25 task. This is accomplished without disturbing in any way standard constructions or dimensions, the only change involved being the shape of the head of the bolts 13, and the employment of the threaded bushing 15, the 30 latter, however, possesses the same diameter 35 as a standard sized bolt.

While I have described what I consider to be the preferred form of the present invention, never the less it will be understood that 40 I do not limit myself to the precise details of construction illustrated and described, but reserve the right to employ such modifications or variations thereof that may be said to fall within the scope of the following 45 claims.

What is claimed is:

1. The combination with the pedestal frame of a locomotive, a pedestal brace and an axle block carried by said frame and located above said brace, of a wedge member inserted between one side of said block and said pedestal frame, said wedge member being provided with a substantially T shaped slot in the lower part thereof which is disposed in 50 the horizontal plane of the axle block, a threaded bushing removably positioned within a threaded opening formed in said brace, 55

the upper end of said bushing being engaged with said wedge to hold the latter in applied engagement with said brace and axle block, 60 and a headed bolt having the shank thereof positioned within said bushing, the head of said bolt being normally located within the slot in said wedge member, and the head of said bolt being so proportioned as to pass 65 through the opening in said brace following the removal of said bushing.

2. The combination with the pedestal frame of a locomotive and the associated axle block and pedestal brace, of a wedge member positioned between one side of said block and said pedestal frame, said wedge member being provided with a substantially T shaped slot in the lower part thereof which is disposed in the horizontal plane of the axle 70 block, a removable exteriorly threaded bushing positioned within a threaded opening formed in said pedestal brace in vertical alignment with said wedge member, the upper end of said bushing being maintained in 75 engagement with the lower portion of the wedge member, and a bolt provided with a head and a threaded shank portion, the shank portion of said bolt being positioned loosely within said bushing, and a head of 80 said bolt being formed so that when the bolt is rotated the head thereof will pass through the restricted portion of the slot in the wedge member, the diameter of said head being less than that of the opening in said pedestal 85 brace, whereby when said bushing is removed said bolt may be withdrawn from its operative position without requiring the removal of the pedestal brace or wedge member.

3. A wedge bolt assembly for locomotive pedestal frames comprising a wedge member having a substantially T shaped slot formed in the bottom thereof, a bolt formed to include a threaded shank and an enlarged head, said head being normally arranged to extend transversely of the slot in the wedge member but so proportioned that when rotated to assume a longitudinal position with respect to said slot the head will be permitted to pass through the restricted portion of the slot, and a threaded bushing for the reception of the shank of said slot, the diameter of said bushing exceeding the greatest diameter of said head, said bushing serving to apply a force to said wedge member opposed to the forces imparted to the wedge member by said bolt.

In testimony whereof I affix my signature.
FRANK C. McENERNY.
